Primary Examiner — Jennifer Rivard*Assistant Examiner* — Jonathan E Fiencke(57) **CLAIM**

The ornamental design for a pool floater for chlorine tablet, as shown and described.

DESCRIPTION

FIG. 1 is a right side view of a pool floater for chlorine tablet shown fully assembled, showing my new design;

FIG. 2 is a top and right side perspective view;

FIG. 3 is bottom and right side perspective view thereof;

FIG. 4 is a bottom and right side perspective view showing the top part of the design article thereof;

FIG. 5 is a top and right side perspective view showing the middle part of the design article;

FIG. 6 is a bottom and right side perspective view thereof; and,

FIG. 7 is a top and right exploded view of the design article showing, the top, middle, and bottom parts thereof.

The broken lines depict portions of the pool floater for chlorine tablet that form no part of the claimed design.
